ROAD MARKER

Chester W. Glasgow, Detroit, Mich.

Application November 7, 1930, Serial No. 494,107

14 Claims. (Cl. 91—45)

My invention relates to road markers and has particular reference to that type of machine which is adapted to form guide lines or stripes on road surfaces.

5 The object of my invention is to improve upon structure illustrated and claimed in my copending application Serial Number 357,945, filed April 25, 1929, and to so arrange an assembly broadly similar to that disclosed therein that the scope 10 of its usefulness may be greatly increased. I contemplate constructing and arranging the paint spray mechanism so that it may be secured in position and its spray controlled from a remote location for the purpose of forming the 15 guide lines or stripes hitherto specified on road surfaces, while at the same time permitting detachment of the spray gun so that it may be utilized for the purpose of painting other objects. In this way a substantially wider field of use- 20 fulness is created and what was formerly useful only for the purpose of marking the roads now constitutes a compact, movable spray painting machine.

Another object of my invention is to eliminate 25 substantially all waste of the paint when performing the road marking operation and at the same time, and by the same means, form a neat, clearcut stripe along a road surface.

As in my copending application above specified, 30 I have provided means whereby the width of the stripe may be varied at will and in the instant application I provide improved means for securing this adjustability.

Still another object of my invention is to in- 35 sure that the edges of the stripe to be painted on the road surface will be sharply drawn and devoid of all smudges caused by overrunning of paint. For this purpose I provide adjustable means for continually exerting pressure upon the 40 road engaging spray limiting means whereby there can be no possibility of the paint seeping out over the road surface under the spray limiting discs.

A further object of my invention is to accom- 45 plish the above set forth advantages and improvements with a unitary, compact structure comprising a minimum of parts.

Various other meritorious features of my in- 50 vention will be apparent from the following de- scription taken in conjunction with the drawings wherein like numerals refer to like figures throughout the several drawings and wherein:

Fig. 1 is a side elevation of my improved ma- chine,

55 Fig. 2 is a front elevation thereof,

Fig. 3 is a section through the wheel and disc supporting axle,

Fig. 4 is an enlarged elevation, partly in section, of my improved detachable spray gun se- 5 curing means,

Fig. 5 is a detail thereof, and

Fig. 6 is a perspective illustrating my improved scraper and container unit.

For the purpose of eliminating all unnecessary expense and procuring simplified structure 10 I utilize a skeleton frame support for the various elements constituting my machine, this skeleton being formed of frame members 10 and 12, each of which are secured to a flanged base 14 which is provided with two forward road engaging 15 wheels 16 and 18 and a rear swivelled road en- gaging wheel 20.

Secured to the base 14 is a prime mover 22, which may be of any desired type, a gasoline or fuel supply tank 24 for said prime mover, and 20 an air compressor unit 26. A compressed air tank 28 is cradled between the supporting frame members 12, these members being braced by cross members 30 and 32. Supported upon a flanged platform 34, which platform is secured to the 25 flanged base 14, is the paint container 36. Various connections extend between the compressor unit, the compressed air tank, and the paint container which need not be described in detail inasmuch as they constitute no part of this invention. 30 Flexible conduits 38 and 40 extend from the paint container 36 to the spray gun 42, the spray from which is controlled by manual manipulation of trigger element 44.

Secured to the flanged base element 14 by 35 means of the straps 46 and 48 is the axle 50, upon the extremities of which the supporting wheels 16 and 18 are rotatable journalled. If desired, an additional brace member 52 may be utilized to provide rigidity of the axle in relation to the 40 flanged base 14, which base is adapted to rest upon said axle as a support for the front end thereof.

One side of the axle 50 is provided with an externally threaded sleeve 54 which is adapted to 45 extend between one outer edge of flange base 14 and the supporting wheel 16. Secondary sleeve members 56 and 58 are provided with annular flanges 60 and 62. A spacer plate 64 is riveted to each outer flange 60, the adjacent faces of 50 the flanges 60 and 62 being retained in spaced apart relation thereby. This construction also permits separation of the flanges for cleaning purposes. Two such secondary sleeve assemblies 55 are threaded onto sleeve 54 and each is adapted to

support between the flanges 60 and 62 a centrally apertured disc 68. These discs are adapted to engage the road surface to be marked and by means of their threaded support may be spaced apart any desired distance. The central aperture 66 in each of the discs 68 is of greater diameter than the spacer plates 64 and for that reason a limited up and down motion of the discs is permitted, which motion permits the road engaging discs to conform to any normal variations in the road surface.

A bar consisting of a horizontal portion 70 and a depending vertical portion 72 is connected by the said portions to the frame channel 12 and the outer extremity of axle 50 respectively. The horizontal portion 70 constitutes a supporting guide for the scraper container elements broadly indicated by the numerals 74 and 76. Slidable along the bar portion 70, and adjustable at any position by means of the set screws 78 are elements 80, each of these elements supports depending cylindrical elements 82, each of which is provided with a centrally apertured closure cap 84 adapted to thread on to the bottom thereof. Extending up through the closure cap 84 is a rod 86, which rod is provided with a transversely extending pin 88 which functions to seat a washer 90. This washer is adapted to form a seat for coil spring 92 which surrounds the upper extremity of rod 86 and is seated at its upper extremity against the element 80. Rotatably supported by the bifurcated end portions 94 of rods 86 are grooved pulleys 96 which are adapted to bear upon the peripheral edge of the road engaging discs 68. The constant pressure of springs 92 acting downwardly upon the rod 86 is transferred to the said road engaging discs, keeping said discs yieldingly but firmly in contact with the road surface which is being marked.

Each of the elements 80 likewise supports a depending rod 98 which functions to support the scraper container elements 74 and 76 respectively. The structure of these elements is clearly illustrated in Fig. 6 and includes a container portion 100 along the outside upper edge of which there is a scraper element 102. A rear outer edge 104 of the scraper element is adapted to lie flush against the face of each inner sleeve flange 62 and the ledge portion 106 thereof is adapted to seat against the peripheral edges of said flanges. In this way the scraper 102 is positioned firmly and the scraper edge 108 thereof will contact the inner faces of the rotating discs 68, thereby scraping off whatever paint adheres thereto and depositing it in the container portion 100. Each container unit may be provided with a valve outlet 110 for the purpose of depositing at will the paint which collects in the container. The valve may be left open so that when the paint reaches a point approximating the half way level of the container it will flow out onto the line being marked.

The mechanism for securing my paint spray gun detachably in position to form the road mark is supported by the angle bar 112 which is secured to the flanged base 14 of the assembly. This mechanism consists of a U-shaped bar 114, the lower arm of which is provided with a notch 116 adapted to seat the nozzle end of the spray gun 42. The said spray gun is provided with a hook 118 which is adapted to be drawn forwardly by the co-operating spring pressed hook 120 which extends through the aperture 122 in the base of the U-shaped bar 114. The upper arm 124 of U-bar 114 supports a saddle shaped ele-

ment 126 in which the butt 128 of spray gun 42 is adapted to seat. The constant forwardly exerted pressure of the spring pressed hook 120 retains the butt portion 128 firmly seated in saddle 126.

The rear upper extremity of the frame is provided with handles 130 and 132 for the purpose of pushing the assembly, and manual means for controlling the volume and pressure of the paint spray are likewise provided. This manual means 10 consists of a small lever 132 which is adapted to actuate a flexible connecting element 134, the opposite extremity of which is provided with an elongated ring 136 which is hooked over the trigger 44 of the spray gun. A flexible casing 138 15 may be utilized to protect the connection 134. Thus it will be seen that for the purpose of removing the spray gun from the position in which it is adapted to direct a spray of paint between the road engaging discs 68 it is only necessary 20 to remove the loop 136 from the trigger and press the hook 120 inwardly against the resistance of its spring. The gun may be then utilized for the purpose of spraying any object desired.

Having illustrated a preferred embodiment of 25 my invention, other modifications will be apparent to those skilled in the art, and for that reason I intend to limit myself only within the scope of the appended claims.

What I claim:

1. In combination with a road marker, a pair of laterally spaced apart floating ground engaging discs, and yielding means constantly exerting a groundward pressure upon said discs.

2. In combination with a road marker, a plurality of laterally spaced apart floating ground engaging discs, means for adjusting the lateral space between said discs, and means for exerting a yielding downward pressure upon each of said discs during rotation thereof.

3. A road marker including, in combination, a plurality of road engaging wheels, a transverse axle rotatably supporting two of said wheels, a plurality of road engaging discs floatingly supported on said axle in laterally spaced apart relation, means for adjusting the lateral spacing between said discs, and means constantly exerting a yielding downward pressure upon each of said discs.

4. A road marker including, in combination, a movable supporting base, paint spray mechanism supported thereon, a plurality of floating ground engaging discs supported in laterally spaced apart relation, means for adjusting each of said discs laterally within predetermined limits, a paint spray gun connected with said spray mechanism and detachably supported to direct a paint spray upon the ground between said discs, and means for constantly maintaining said discs in contact with the ground.

5. In combination with a road marker of the class described, a pair of floating ground engaging discs adapted to limit the paint spray, scraping elements supported against the adjacent faces of each of said discs, and yielding means urging said discs against the ground.

6. In combination with a road marker of the class described, a pair of floating ground engaging discs adapted to limit the paint spray, and scraping elements supported against the adjacent faces of each of said discs, said scraping elements including a container unit for retaining the paint scraped from the discs thereby.

7. In combination with a road marker of the class described, a plurality of ground engaging

- discs adapted to limit the spray of paint, means for adjusting each of said discs laterally, yieldable means normally exerting groundward pressure upon each of said discs, a scraper element supported in contacting relation to adjacent faces of each of said discs, and a single means for laterally adjusting said yieldable means and said scraper element in conformity with the lateral disc adjustment. 5
10. 8. A road marker including, in combination, a movable base supported upon roller elements, paint spray mechanism supported upon said base, a plurality of floating road engaging discs adapted to limit the paint spray, said means including a spray gun, means for detachably positioning said gun to direct a paint spray upon the ground between said discs, means whereby said spray gun may be manipulated from a remote point, and means for detachably connecting said remote control means to said gun. 15
9. A road marker including, in combination, a roller supported base including a pair of rollers mounted on the extremities of a transverse axle located forwardly of said base, an externally threaded sleeve extending along a portion of said axle, a plurality of ground engaging discs supported upon said sleeve, the supporting means therefor being in threaded engagement with said sleeve for adjustment laterally therealong, yieldable means exerting a constant downward pressure upon each of said discs, paint spray mechanism supported upon said base and adapted to direct a spray of paint upon the ground between said discs, and means detachably connected to said gun permitting remote control thereof. 20
10. In combination with mechanism of the class described, a supporting axle, an externally threaded sleeve mounted thereon, a pair of internally threaded hubs mounted upon said sleeve, and road engaging discs floatingly supported upon said hubs. 25
11. In combination with mechanism of the class described, a pair of internally threaded component hub members having radially extending annular flanges, an annular spacing element separating said flanges and terminating inwardly of the outer periphery of said radial flanges, and an annular disc mounted between said flanges whereby the radial movement of said disc in any direction is limited by said spacer element. 10
12. Mechanism of the class described including a pair of floating road engaging discs, yieldable means urging each of said discs toward the road, scraper elements associated with each of said discs and including a portion in contact with the inner face of each disc, and means positioning the yieldable member and scraper associated with each respective disc operable as a unit to adjust the combination laterally. 15
13. In a highway marker, the combination with a spray gun for discharging marking material towards the highway, rotating discs for confining the application of the marking material on the highway to a stripe of predetermined width and means for removing excess marking material from the inside faces of the discs, of means for catching and storing the excess marking material removed from the discs. 20
14. The combination with a pair of spaced apart spray limiting road engaging discs of a scraper unit including a container portion supported contiguous to the inner face of each of said discs, each scraper unit provided with a lip forming an extension of one side wall of the container which lip is adapted to contact the inner face of the disc to remove paint therefrom and discharge the same into the container. 25

CHESTER W. GLASGOW.
